UNITED STATES PATENT OFFICE.

DONALD D. ORMSBY AND CHARLES H. LOGUE, OF SYRACUSE, NEW YORK, ASSIGNEES TO BROWN-LIPE-CHAPIN CO., OF SYRACUSE, NEW YORK, A CORPORATION OF NEW YORK.

GEAR-LAPPING MACHINE.

1,304,699.

Specification of Letters Patent. Patented May 27, 1919.

Application filed January 19, 1916. Serial No. 72,999.

To all whom it may concern:

Be it known that we, DONALD D. ORMSBY and CHARLES H. LOGUE, citizens of the United States, and residents of Syracuse, in the county of Onondaga and State of New York, have invented a certain new and useful Gear-Lapping Machine, of which the following is a specification.

Our invention has for its object a machine for "working in" or lapping the teeth of gears to correct the generating of the conjugate curves of the teeth of two gears which are to run in mesh in the mechanism in which they are to be embodied; which machine is particularly simple in construction and highly efficient, durable, rapid and accurate in use; and the invention consists in the combinations and constructions herein-after set forth, and claimed.

In describing this invention, reference is had to the accompanying drawings in which like characters designate corresponding parts in all the views.

Figure 1 is a plan view, partly in section, of one embodiment of a machine embodying our invention.

Fig. 2 is an elevation partly broken away of the machine shown in Fig. 1, the oscillation of parts thereof being indicated in dotted lines.

Fig. 3 is an elevation, partly in section and partly broken away, looking upwardly in Fig. 1.

Fig. 4 is a sectional view, parts being omitted, taken on the plane of line 4-4 Fig. 1, looking to the left.

Fig. 5 is a plan view of the hand wheel and contiguous parts shown in Fig. 4.

This gear lapping machine comprises generally, means for supporting and rotating the gears while in mesh and means for moving the support for one of the gears to carry said gear toward and from the other gear and bring them into full mesh and partly out of mesh during the rotation of the gears, to correct the generating of the conjugate curves of the teeth of the gears.

The machine here illustrated comprises a carriage having a rotating support for one gear, a carriage having a rotating support for the second gear arranged to hold the second gear in mesh with the first gear,

carriage being movable back and forth to carry the second gear toward and from the first gear during the rotation of the gears. 55

The illustrated form of our machine is for working in two bevel gears, and the carriage for the second gear is mounted to oscillate about an axis intersecting the axis of the rotating support of the first gear, and the support of the second gear is arranged with its axis radially relatively to the axes of the support for the first gear and the oscillating carriage. In other words, the axis of the oscillating carriage is arranged in a line which intersects the apex of the pitch cones of the two gears, it being understood that for the proper running of bevel gears the apices of the pitch cones of the two gears are nearly or substantially coincident. 60 65 70

Preferably in order that the machine may be adjusted to different sizes of gears, the rotating supports for the gears are adjustable axially.

1 designates the support for one gear 75 which is here shown as a head having a face plate 2 to which the gear 3 is secured, the head being mounted upon a rotating shaft or spindle 4 journaled in a suitable bearing 5 supported by a carriage 6 movable 80 in suitable guides along the main frame or bed 7.

8 is the oscillating carriage, said carriage being pivoted at 9 to the frame or bed 7 with its axis intersecting at a right angle, 85 the axis of the shaft 4 and gear supporting carriage 1.

10 is a support for the second gear 11, said support being a shaft suitably fixed in a rotatable sleeve 12 journaled in suitable 90 bearings 13 supported, as hereinafter described, and the shaft being arranged eccentric to the axis 9 of the carriage 8 and radially relatively to the axis of the gear support 1 and its shaft 4, the arrangement 95 of the supports 1 and 8 being such that the axial line of the carriage 8 intersects the apices of the pitch cones of the gears 3 and 11. The bearings 13 for the sleeve 12 and the shaft 10 are supported by brackets 14 100 projecting from a carriage 15 adjustable along a suitable guide 16 provided on the oscillating carriage 8, and extending radially relatively to the axis 9 of the carriage 8.

The carriage 15 is adjustable along its guide 16 by means of an adjusting screw 17 having a handle wheel 18 at its outer end, the amount of the adjustment being determined 5 by a scale on the handle and an indicator 19 fixed relatively to the handle wheel. The carriage 15 is held in its adjusted position by means of clamping members 20.

The carriage 6 which carries the spindle 10 4 supporting the gear 3 is also adjustable to shift the gear 3 axially, it being movable along the bed 7 by means of an adjusting screw 21, Fig. 3 similar to the screw 17. The gears are rotated by power applied to 15 one of the shafts 4 or 10, and the carriage 8 is oscillated by power transmitting connections between one of these shafts and the carriage 8.

In this embodiment of our invention, the 20 sleeve 12 which encircles and rotates with the shaft 10 is provided with a pulley 22 thereon between the ends thereof and between the bearings 13, by means of which pulley power can be applied to the shaft 10 25 through a suitable belt. The motion is transmitted to the gear 3 and its support 1 and spindle 4; and the carriage 8 is actuated by power transmitting connections interposed between the shaft 4, and said carriage 8.

20 The power transmitting connections here illustrated include a worm 23, Fig. 1, mounted on the spindle 4, a worm gear 24, Figs. 1 and 3, meshing with the worm 23, a shaft 25 extending crosswise of the shaft 4 and 35 upon which the spiral gear 24 is mounted, eccentric means mounted on the shaft 25 including a disk 26 having an eccentric pin 27 on which is mounted a suitable block or bearing 28, a rock arm or link 29 having a 40 slot 30 in which the block 28 slides, a rock shaft 31 parallel with the shaft 25 and upon one end of which the rock arm 29 is mounted, a rock arm 32 mounted on the other end of the rock shaft 31, and a link 33 connected 45 at one end of the rock arm 32 and its other end to the carriage 8.

The shafts 25 and 31 are supported in suitable bearings 34 and 35 provided on the carriage 6. The amount of throw or the 50 movement of the rock shaft 31 and its arm 32 can be adjusted by moving the eccentric block 28 radially relatively to the disk 26, this adjustment being effected in any suitable manner as by a screw 36, Fig. 3, extending 55 radially of the disk 26 or the guide way in which the block 28 slides. The angle of the rock arm 29 relatively to the rock shaft 31 may be varied to conform to the adjustment of the eccentric pin 27 and the block 28, by loosening a locking device 37 on the shaft 31, which device locks the rock arm 29 to the shaft 31, and turning the rock shaft 31 relatively to the rock arm 29 to conform to the new position of the eccentric 27, and 65 tightening the device 37, it being necessary

to disconnect the rock arm 32 or the link 33 from the carriage 8 during such turning of the rock shaft.

A casing 38 incloses the parts 26, 29, 37 and contiguous parts, this casing being removed in Fig. 1.

The link 33 is connected to the carriage 3 by means of a movable pivot pin 39, Figs. 1 and 3 which is connected to a locking bolt 40 so that the pivot pin 39 can only be removed and replaced (as before and after the throw of the eccentric pin 27 and the block 28, and the relative angular position of the rock arm 31 have been adjusted) when the carriage 8 is in its starting position. This 80 locking pin 40 is movable through a passage 41, Fig. 3 in the carriage 8, and into a socket 42 formed in the carriage 6. The passage 41 and socket 42 are in alinement when the carriage 8 is in its starting position, that is, its 85 central position in which it supports the bevel gear or pinion 11 so that the axial line of said gear is at a right angle to the axis of the other bevel 3 when the gears are in normal meshing relation and the apices of the 90 pitch cones of the gears are coincident. The pivot pin 39 and locking pin 40 are connected together by a rocking arm or lever 43 pivoted at 44 between its ends to lugs 45 projecting from the carriage 8 and at its 95 opposite ends at 46, 47 to the pins, 39, 40, respectively. Hence, the pivot pin 39 cannot be removed unless the carriage 8 is moved into such position that the passage 41 is aligned with the socket 42. Therefore before 100 an adjustment of the eccentric bearing block 28 or the rock arm 32 can be effected, it is necessary to lock the carriage 8 in its starting or central position, and before the pivot pin 39 can be replaced it is necessary that 105 the carriage 8 be moved to its starting position if in the meantime it has been moved out of such position. Hence, after an adjustment of the eccentric bearing block 28 has been made, it is necessary to rotate the shaft 110 25 by hand in order to position the eccentric in such angular relation that it will operate to move the carriage equal distances to the right and the left of its central position.

The link 33 is composed of two sections 115 48, 49 with a buffer spring between them, the section 48 being a barrel, the section 49 being a rod extending into the barrel, and the spring 50 being compressible between a head 51 on the inner end of the rod and a 120 plug 52 closing the end of the barrel and through which plug the rod extends. The barrel is provided with a bearing 53 pivoted at 54 to the rock arm 32, and the rod 49 extends into the socket or bearing 55 pivoted 125 at 56 on the pin 39.

A suitable pulley 57 and drum 58 are provided on the shaft 4 for connection respectively with an oil pump, and a brake for placing a load on the gears.

In operation, the bevel gears are placed upon their respective supports 1 and 10, these parts having been adjusted axially to conform to the sizes of the gears to be lapped or "worked in". The throw of the eccentric 27 and the rock arm 32 are adjusted properly to move the carriage 8 so that the gear or pinion 11 on the spindle 10 will be moved laterally inwardly toward the gear on the support 1, to mesh the teeth beyond their normal meshing relation, that is, beyond the pitch line, and outwardly beyond their normal pitch line but not entirely out of mesh. Power is then applied to the pulley 22 and this power is transferred through the gears 11 to the carriage or support 1, shaft 4, through the worm 23, spiral gear 24 and parts connected thereto, to the carriage 8. If necessary abrading material as emery dust may be applied to the gears 11 and 3 on the supports but in most cases it is not necessary to use abrading material. Owing to the oscillating movement of the carriage 8 and the rotation of the gears 11 and 3 thereof, the "working in" or the correcting of the conjugate curves of any two gears that are to run together, is quickly accomplished, so that they work substantially noiselessly, the average time for each set of gears being less than thirty seconds.

What we claim is:

1. A gear lapping machine comprising a rotating support for one gear, an oscillating carriage having a rotating support for a second gear located eccentric to its axis of oscillation, means for rotating one of the supports, and means for oscillating the carriage during the rotation of the supports, substantially as and for the purpose specified.

2. A gear lapping machine comprising a rotating support for one gear, an oscillating carriage having a rotating support for a second gear, means for rotating one of the supports, and means for oscillating the carriage during the rotation of the supports including means for varying the throw of the carriage, substantially as and for the purpose described.

3. A bevel gear lapping machine comprising a rotating support for one gear, an oscillating carriage having a rotating support for a second gear, the support being located eccentric to the axis of oscillation of the carriage and the carriage being arranged with its axial line intersecting the axis of rotation of the support for first gear, means for rotating one of the supports, and means for oscillating the carriage, substantially as and for the purpose set forth.

4. A bevel gear lapping machine comprising a rotating support for a bevel gear, a carriage having a rotating support for a second bevel gear arranged at an angle to the axis of the support for the first gear

to hold the second bevel gear in mesh with the first bevel gear, the carriage being movable back and forth to carry the second gear toward and from the first gear during the rotation of the gears for correcting the conjugate curves of the gear teeth, the rotating support of one of the gears being adjustable axially, and means for rotating the gears and for simultaneously oscillating the carriage, substantially as and for the purpose described.

5. A bevel gear lapping machine comprising a rotating support for one bevel gear, and an oscillating carriage having a rotating support for a second bevel gear, the support being arranged with their axes at an angle with each other in position to hold the gears in mesh, and the carriage being arranged with its axis intersecting the apex of the pitch cones of the gears, each of the supports for the gears being adjustable axially, substantially as and for the purpose specified.

6. A bevel gear lapping machine comprising a rotating support for one bevel gear, an oscillating carriage having a rotating support for a second bevel gear, arranged radially relatively to the axis of the carriage in position to hold the second bevel gear in mesh with the first bevel gear, the carriage being arranged with its axis intersecting the apex of the pitch cones of the gears, means for rotating the support of one of the gears, and power transmitting means between the rotating support of one gear and the carriage to oscillate the carriage, substantially as and for the purpose specified.

7. A bevel gear lapping machine comprising a rotating support for one gear, a carriage having a rotating support for a second gear arranged to hold the second gear in mesh with the first gear, the carriage being movable back and forth to carry the second gear toward and from the first gear for correcting the conjugate curves of the teeth, means for rotating one of the gears, and means for actuating the carriage including means adjustable to vary the throw of the carriage, substantially as and for the purpose described.

8. A bevel gear lapping machine comprising a rotating support for one gear, a carriage having a rotating support for a second gear, arranged to hold the second gear in mesh with the first gear, the carriage being movable back and forth to carry the second gear toward and from the first gear for correcting the conjugate curves of the teeth, means for rotating one of the gears, and means for actuating the carriage including an eccentric pin, a rock shaft, a part connecting the eccentric pin and the rock shaft and a rock arm mounted on said shaft and connected to the carriage, the eccentric pin be-

- ing adjustable radially and the rock arm being adjustable to change the angle thereof, substantially as and for the purpose specified.
5. 9. A bevel gear, lapping machine comprising a rotating support for one bevel gear, and an oscillating carriage having a rotating support for a second gear arranged at an angle to the axis of the support for the 10 first gear, the axial line of the carriage extending crosswise of the axes of the supports, each of the supports being adjustable axially, means for rotating one of the gears, and means for oscillating the carriage including means for adjusting the throw of the carriage, substantially as and for the purpose set forth.
10. A gear lapping machine comprising a frame, a rotating spindle journaled in the 20 frame, a gear support mounted on the spindle and adjustable axially thereof, an oscillating carriage pivoted to the frame on an axis intersecting the axis of the rotating support for the first gear, a second carriage 25 mounted on the oscillating carriage, and movable radially thereof, a rotating spindle carried by the last mentioned carriage and arranged radially relatively to the axis of the oscillating carriage, and having means 30 for supporting a gear in mesh with the former gear, means for rotating one of the rotating spindles, and power transmitting means between the first mentioned rotating spindle and the oscillating carriage, substantially as and for the purpose described.
11. A gear lapping machine comprising a frame, a rotating spindle journaled in the frame, a gear support mounted on the spindle and adjustable axially thereof, an oscillating carriage pivoted to the frame on an 40 axis intersecting the axis of the rotating spindle, a second carriage mounted on the oscillating carriage, and movable radially thereof, a rotating spindle carried by the last 45 mentioned carriage and arranged radially relatively to the axis of the oscillating carriage, and having means for supporting a gear in mesh with the gear on the former carriage, means for rotating one of the spindles, and power transmitting means between 50 the first mentioned spindle and the oscillating carriage, substantially as and for the purpose specified.
12. A gear lapping machine comprising a 55 rotating support for one gear, a carriage having a rotating support for a second gear arranged to hold the second gear in mesh with the first gear, the carriage being movable back and forth and arranged to carry the second gear toward and from the first 60 gear during the actuation of the carriage, means for rotating the support for one gear, means for actuating the carriage, said means being adjustable to vary the throw of the carriage and including a pivot pin connecting 65 said means and the carriage, a locking bolt for locking the carriage in its starting position, means for holding the bolt from movement when the carriage is out of its starting position, and a coupling between 70 the pivot pin and the locking bolt whereby when the pivot pin is removed or replaced the locking bolt is moved into and out of its locking position, substantially as and for the purpose described.
13. A gear lapping machine comprising a 75 rotating support for one gear, a carriage having a rotating support for a second gear arranged to hold the second gear in mesh with the first gear, the carriage being movable back and forth and arranged to carry the second gear toward and from the first gear during the actuation of the carriage, means for rotating the support for one gear, means for actuating the carriage, said means 80 being adjustable to vary the throw of the carriage and including a pivot pin connecting said means and the carriage, a locking bolt for locking the carriage in its starting position, means for holding the bolt from movement when the carriage is out of its starting position, and a lever pivoted between 85 its ends to the carriage and at its ends to the pin and the bolt, substantially as and for the purpose specified.
14. The combination of a stationary part formed with a socket, a movable carriage, actuating means for the carriage adjustable to vary the movement of the carriage, the carriage having a passage normally in alignment with the socket, a pin for connecting the actuating means to the carriage, and a lever pivoted between its ends to the carriage and at its ends to the pin and the bolt, substantially as and for the purpose set forth.
- In testimony whereof, we have hereunto signed our names at Syracuse, in the county of Onondaga, in the State of New York, this 20 day of December, 1915.
- DONALD D. ORMSBY.
CHARLES H. LOGUE.
